UNITED STATES PATENT OFFICE.

ANDREW B. CLAYTON, OF UNION, NEW JERSEY, ASSIGNOR TO THE SINGER MANUFACTURING COMPANY, OF ELIZABETH, NEW JERSEY, A CORPORATION OF NEW JERSEY.

PRESSER MECHANISM FOR SEWING MACHINES.

Application filed November 12, 1926. Serial No. 147,893.

This invention relates to sewing machines and more particularly to the presser mechanism of clamp-feed or top-feed sewing machines.

5 Clamp-feed mechanisms, for example, commonly comprise a lower four-motion feed-dog and an upper four-motion feed-foot working in unison to clamp the work between them, feed it a stitch-length, release the work, and return to initial position for repetition of the feeding cycle.

Top-feed mechanisms are similar to clamp-feed mechanisms with the lower four-motion feed-dog omitted; the upper feed-foot 15 acting to slide the work over the throat-plate during the feeding stroke.

With feeds of these types it is customary to provide a presser-foot to hold the work under control when released by the feeding 20 means. Such presser-foot is commonly carried by a spring-pressed presser-bar which latter is so connected to the lifting mechanism for the upper feed-foot that the presser-foot is lifted by upward reaction of 25 such mechanism against the presser-bar when the feed-foot is lowered into engagement with the work, and the presser-foot is lowered into engagement with the work when the upper feed-foot is lifted; the 30 presser-foot and feed-foot being alternately subjected to the heavy pressure of the presser-bar spring. This alternate lifting and lowering of the two feet produces an objectionable hammering as the speed of the 35 machine is increased and limits the effective speed of the machine.

Clamp-feed machines as heretofore constructed have another objectionable characteristic, residing in the chopping action of 40 the top and bottom feed-dogs upon the chain of stitches, when chaining off, it being necessary to arrange portions of both top and bottom feed-dogs in rear of the presser-foot to feed the chain when the presser-foot is lifted. This chopping action mutilates the chain and limits the speed at which the 45 machine will chain off.

It is an object of the present improvement to reduce the hammering action of a top- 50 feed and presser-mechanism and to provide for chaining off freely at higher speeds.

To these ends provision is made for allowing the presser-foot to remain continuously in engagement with the work during 55 the sewing. The presser-foot is prefer-

ably carried by the lower part or section of a two-part presser-bar, between which parts a light expansion spring is interposed. The usual manual lifting mechanism is applied to the lower presser-bar section, which may 60 be called the main presser-bar, while the automatic top-feed and presser-lifting mechanism is applied to the upper section of the presser-bar, which may be termed an auxiliary presser-bar. The result is that the 65 presser-foot is not automatically lifted from the work but remains continuously in engagement with the work during the sewing, being pressed upon the work by the heavy 70 pressure of the usual presser-bar spring when the feed-foot is lifted for its return stroke, and being relieved of such heavy pressure but still under the light pressure of the expansion spring during the feeding 75 stroke.

Only one feed-dog or member, preferably the lower, is arranged directly in rear of the sewing point to engage and feed the chain which is thus not subjected to the chopping action of two coacting toothed 80 feed-members. The presser-foot is preferably extended rearwardly over the lower feed-dog while the upper feed-dog or foot is disposed wholly at one side of the line of sewing. The relief of the pressure during the feed-stroke avoids an objectionable drag of the presser-foot upon the work. Also the load on the upper-feed mechanism is reduced since it is not called upon to overcome the inertia of and reciprocate the main 85 presser-bar. The present improvement maintains a heavy pressure on the presser-foot when needed to control the work and relieves the presser-foot of such pressure during the feed but does not lift the presser- 90 foot from the work.

In the accompanying drawings, Fig. 1 is an end elevation of a sewing machine embodying the invention. Fig. 2 is a sectional view of the head at the end of the bracket-arm in the plane of the needle- and presser-bars. Fig. 3 is a section on the line 3—3, Fig. 1. Fig. 4 is a plan view of the machine bed. Fig. 5 is a rear elevation of the machine. Fig. 6 is a top plan view, partly in section, of the mechanism at the free end of the bracket-arm, and Fig. 7 is a top plan view of the top-feed-foot and presser-foot showing their cooperative relation with the bottom feed-dog and needle. 100 105 110

The invention is shown as embodied in a sewing machine having a frame comprising a bed 1, standard 2 and bracket-arm 3 terminating in the head 4. A flat cloth-plate 5 is supported above the bed 1.

The stitch-forming mechanism comprises the usual reciprocating needle 6 and thread-carrying looper 7. The needle 6 is carried by the needle-bar 8 which is actuated by the link connection 9 with the crank-arm 10 on the oscillatory needle-driving shaft 11. The looper 7 is actuated from the lower main-shaft 12 by mechanism constructed substantially in accordance with the disclosure of the patent to DeVoe, No. 1,100,124, of June 16, 1914.

The particular machine illustrated is provided with clamp-feeding mechanism comprising a lower four-motion feed-dog 13 and an upper four-motion feed-foot 14. The feed-dog 13 is mounted on the feed-bar 15 pivotally supported at 16 on the feed-rocker 17 journaled at 18 on the bed 1. Feed-lift movements are imparted to the feed-bar 15 by means of the eccentric 19 on the main-shaft 12; which eccentric is embraced by the strapped end of a slide-pin 20 working in the feed-bar. Feed-advancing movements are imparted to the feed-rocker 17 by means of the adjustable eccentric 21 on the main-shaft 12, which eccentric is connected by the pitman 22 to the pin 23 carried by the feed-rocker 17.

The upper four-motion feed-foot 14 is carried by the feed-bar 24 which is pivotally hung from a pin 25 on a block 26 slidably mounted on the bearing bushing 27 in which and the lower bushing 27' the main presser-bar 28 carrying the presser-foot 29 is slidably journaled. The bottom feed-dog 13 has a portion 13^a, Fig. 7, directly in rear of the needle 6 and a portion alongside the needle. The presser-foot 29 is extended in rear of the needle so as to work directly over the portion 13^a of the bottom feed-dog. The top-feed member 14 is wholly at one side of the line of stitching and does not bear upon the stitched zone of the work. Feed-and-return movements are imparted to the feed-bar 24 by means of the link-connection 30 with the arm 31 fixed to the rock-shaft 32 having fixed to its rear end a crank-arm 33 connected by a link 34 to the slotted arm 35 of the feed-rocker 36 journaled in the bearings 18 and connected to the feed-rocker 17 by means of an extension of the pin 23, Fig. 5, which enters a slide-block 37 fitted to the slot 38 in the feed-rocker 36, whereby the feed-rockers 17 and 36 are moved in unison.

Feed-lift movements are imparted to the block 26 and feed-bar 24 by means of a toggle device comprising toggle links 39, 40. Toggle-link 39 is of angular or bellcrank form and is connected at its lower end to the

pin 41 on the block 26. At its upper end the toggle-link 39 is connected by the screw-pin 42 to the lower end of the toggle-link 40. Toggle-link 40 is hung from the lateral pin 43 on the block 44 fixed to the auxiliary presser-bar or presser-bar section 45 journaled in the sleeve 27 in alinement with the main presser-bar or lower presser-bar section 28. A weak expansion coil-spring 46, Fig. 2, housed in a bore in the upper presser-bar section 45 is interposed between the presser-bar sections 28 and 45 and serves as an auxiliary presser-bar spring to maintain the presser-foot 29 lightly in engagement with the work when the upper presser-bar section 45 is lifted against the pressure of the heavy leaf-spring 47 by the straightening of the toggle links 39, 40; bringing the pivot points 41, 42 and 43 into substantial alinement, as shown in Figs. 1, 2 and 3. The auxiliary presser-bar or upper presser-bar section 45 is held against turning movements by a forked extension 48 of the block 44 which embraces the needle-bar bearing bushing 49, Figs. 1 and 2.

The toggle-links 39 and 40 are actuated by a link 50 which is connected at 51 to the toggle-link 39 and at its other end is adjustably connected at 52 to the slotted arm 53 fixed to the rock-shaft 54 to which is also fixed the pin 55 entering the sleeve 56 pivoted on the crank-pin 57 on the rearward extension of the crank-arm 10 fixed to the shaft 11.

It will be understood that during the feeding stroke of the feed-dog 13 and feed-foot 14, the work is clamped between them under the reactionary pressure of the leaf-spring 47 and that the presser-foot 29 is not lifted from the work but is pressed lightly thereagainst by the light spring 46. During the return movement of the feed-dog 13 and feed-foot 14 the leaf-spring 47 forces the auxiliary presser-bar 45 down upon the main presser-bar 28 and the full pressure of the leaf-spring 47 is transmitted to the presser-foot 29 to hold the work under control before released by separation of the feed-dog 13 and feed-foot 14. It also follows that the work is firmly clamped between the feeding elements 13, 14 before the heavy pressure of the presser-foot 29 on the work is reduced. In chaining off, the portion 13^a of the bottom feed-dog engages the chain of stitches issuing rearwardly from the sewing point and feeds such chain under the light pressure of the presser-foot 29 which is not lifted during the feeding stroke of the feed-members 13, 14. There is consequently no chopping or mutilation of the chain.

The presser-foot 29 and feed-foot 14 may be manually lifted by the usual hand cam-lever 58 or treadle-controlled lever 59 which operatively engage the slide-block 60 having 130

spaced lugs 61 slidably embracing the presser-bar section 28 to which is fixed, between the lugs 61, a collar 62.

While the invention is disclosed as embodied in a clamp-feed machine it is obvious that in certain of its aspects it is useful in connection with a top-feed mechanism whether accompanied by a bottom-feed mechanism or not.

10 Having thus set forth the nature of the invention, what I claim herein is:

1. In a sewing machine, the combination with an upper four-motion feed-foot, of a spring-pressed presser-foot, and automatic

15 means for reducing the pressure of the presser-foot upon the work during the feeding stroke of the feed-foot, without lifting the presser-foot from the work.

2. In a sewing machine, the combination 20 with a four-motion upper feed-foot, of a presser-foot, heavy and light springs pressing the presser-foot upon the work, and automatic means for lifting the pressure of the heavy spring off of the presser-foot during the feeding stroke of the feed-foot.

3. In a sewing machine, the combination 30 with an upper four-motion feed-foot, of a presser-bar constructed in two parts with a light expansion spring interposed between such parts, a heavy spring pressing upon the upper part of the presser-bar, a presser-foot carried by the lower part of the presser-bar, and automatic means for lifting the upper part of the presser-bar to relieve the pressure of the heavy spring on the lower presser-bar part during the feeding stroke of the upper feed-foot.

4. In a sewing machine, an upper feed-foot, an upper feed-bar, a presser-bar having 40 two relatively movable parts with a light expansion spring acting between such parts, a heavy spring pressing downwardly upon the lower presser-bar part through the upper presser-bar part, means reacting downwardly against the feed-bar for periodically lifting the upper part of the presser-bar against the force of said heavy spring, said means also serving to periodically lift the feed-bar, and means for imparting feed-and-return movements to the feed-bar.

5. In a sewing machine, in combination,

an upper four-motion feed-bar, a feed-foot carried by said feed-bar, a presser-bar, a presser-foot carried by said presser-bar, a heavy spring exerting downward pressure 55 upon said presser-bar, means for raising and lowering said feed-bar and periodically transferring the pressure of said spring from said presser-bar to said feed-bar, a light spring acting on said presser-bar to retain the presser-foot in engagement with the work when the pressure of the heavy spring is shifted to the feed-bar, and means for imparting feed-and-return movements to the feed-bar. 60

6. In a sewing machine, an upper feed-foot, an upper feed-bar, a presser-foot, a main presser-bar carrying said presser-foot, a light spring acting upon the main presser-bar during the sewing to maintain the presser-foot continuously in engagement with the work, an auxiliary presser-bar movable independently of the main presser-bar and acting at times to exert increased downward pressure upon the main presser-bar, a heavy spring acting upon said auxiliary presser-bar, means reacting upwardly against said auxiliary presser-bar and heavy spring for forcing said feed-foot upon the work, said means also acting at another period of the feeding cycle to lift the feed-foot and permit the pressure of the auxiliary presser-bar to be transferred to the main presser-bar, and means for imparting feed-and-return movements to the feed-bar. 70 75

7. In a sewing machine, the combination with stitch-forming mechanism including a reciprocating needle, of feeding mechanism including top and bottom four-motion feed-members of which only the bottom feed-member engages the work directly in rear of the needle, and a spring-pressed presser member having a portion disposed in rear of the needle above the bottom-feed, and means for reducing the downward pressure 90 of the presser-foot during the feeding stroke of the feed-members, without lifting the presser-foot. 95

In testimony whereof, I have signed my name to this specification.

ANDREW B. CLAYTON.
